FISH LURE

Ewell J. Harris, Rte. 3, Box 135A, Lot 13,
Adrian, Mich. 49221

Filed June 29, 1972, Ser. No. 267,407

Term of patent 14 years

Int. Cl. D22—05

U.S. Cl. D22—27

FIG. 2.

FIG. 3.

FIG. 1.

FIG. 4.

FIG. 5.

FIG. 1 is a side view of a fish lure embodying my new design;

FIG. 2 is a top plan view thereof;

FIG. 3 is an end view taken from the left of FIG. 2;

FIG. 4 is an end view taken from the right of FIG. 2 with the hook section shown in an alternate position; and

FIG. 5 is a bottom plan view thereof.

I claim:

The ornamental design for a fish lure, substantially as shown.
